(57) **CLAIM**

The ornamental design for a collar for use with a clamp, as shown and described.

DESCRIPTION

FIG. 1 is a perspective view of a collar for use with a clamp according to the invention.

FIG. 2 is a Plan view of a collar for use with a clamp according to the invention.

FIG. 3 is a view in direction of arrow 3-3 of a collar for use with a clamp according to the invention.

FIG. 4 is a view in direction of arrow 4-4 of a collar for use with a clamp according to the invention; and,

FIG. 5 is a view from bottom of a collar for use with a clamp according to the invention.

The broken line showing of structural features is included for the purpose of illustrating non-claimed subject matter and forms no part of the claimed design.

The claimed design is particularly characterized by the external shape of the collar.
